UNITED STATES PATENT OFFICE.

LUTHER L. KNOX, OF BELLEVUE, PENNSYLVANIA, ASSIGNOR TO BIAW-KNOX COMPANY, OF PITTSBURGH, PENNSYLVANIA, A CORPORATION OF NEW JERSEY.

HOLLOW WATER-COOLED STRUCTURE.

Application filed December 20, 1920. Serial No. 431,876.

To all whom it may concern:

Be it known that I, LUTHER L. KNOX, a citizen of the United States, residing at Bellevue, county of Allegheny, and State of Pennsylvania, have invented a new and useful Improvement in Hollow Water-Cooled Structures, of which the following is a full, clear, and exact description, reference being had to the accompanying drawings, forming part of this specification, in which—

Figure 1 is a longitudinal section of a portion of one form of structure embodying my invention;

Figure 2 is a section on the line II—II of Figure 1;

Figure 3 is a plan view, broken away, showing a portion of another form of structure embodying my invention;

Figure 4 is a section on the line IV—IV of Figure 3;

Figure 5 is a detail sectional view on a larger scale showing one of the pockets; and

Figure 6 is an inverted sectional plan view of the parts shown in Figure 5.

My invention has relation to certain new and useful improvements in hollow water-cooled structures, such as are used in cooling furnace walls, and in water-cooled floors, bulk heads and the like.

In the use of structures of this character it is extremely desirable to prevent the formation of steam pockets within the structure since such formation is frequently accompanied by disastrous results.

The object of my invention is to provide means of efficient and effective character whereby the formation of such pockets is entirely eliminated.

The nature of my invention will be best understood by reference to the accompanying drawings in which I have shown two different embodiments thereof, which will now be described, it being premised, however, that it is illustrative only, and that it can take other forms within the spirit and scope of the appended claims.

Referring first to that form of my invention shown in Figures 1 and 2, the numeral 2 designates a hollow sheet metal structure which is designed to be set in a vertical position and which is provided with any usual or suitable means for the introduction of a cooling medium, preferably water.

In accordance with my invention I provide the top wall of this structure with one or more off-set portions 3, these off-set portions being at the highest point of the structure and forming each a pocket 4, which is at a higher level than any part of the interior of the structure.

5 designates an off-take pipe for the heated water and steam, this pipe having as many branches 6 as there are pockets 4, each branch extending upwardly to about the level of the bottom of the pocket and being open at its upper end. These branch pipes may be secured in any suitable way, as by setting them in spiders 7. Preferably the spiders are provided with guard lugs 8 in order to prevent the upper end of the pipes from being seated too high.

It will be readily seen that the heated water in order to escape must rise into the 75 pockets 4 and that any and all steam which may be formed will escape into said pockets and pass out through the escape pipe with the heated water.

Figures 3 and 4 show the application of 80 my invention to a hollow water-cooled metal structure which is designed to be placed in horizontal position, as in a water-cooled floor. In this case the pockets 4^a are formed in the top horizontal wall of the structure, the off-take pipes 5^a and 6^a being arranged in the same manner as in the form first described.

It will be readily understood that the number and arrangement of the pockets of 90 any particular structure will depend upon the character and shape of the structure.

The advantage of my invention will be apparent since the provision of the off-set pockets gives a free escape to all steam which 95 may form in the interior of the structure and permits steam to escape freely with the heated water.

I claim:

1. A hollow structure adapted to have a 100 cooling medium circulated therethrough, the top wall of such structure having therein an upwardly off-set pocket communicating with the interior of the structure, an off-take pipe extending upwardly to the said 105 pocket, and means limiting the upward extension of said pipe, substantially as described.

2. A hollow structure adapted to have a 110 cooling medium circulated therethrough, the

top wall of such structure having therein an upwardly off-set pocket communicating with the interior of the structure, and an off-take pipe extending upwardly to the said pocket, the structure having internal means cooperating with said pocket for seating and supporting the said pipe, substantially as described.

3. A hollow metal structure adapted to have a cooling medium circulated therethrough, said structure having its top wall

provided with a plurality of off-set portions forming interior pockets at a higher level than the interior of the structure proper, an off-take pipe having a branch extending to each of the said pockets, and means for supporting each of said branches in operative position, substantially as described.

In testimony whereof, I have hereunto set my hand.

LUTHER L. KNOX.
